UNITED STATES PATENT OFFICE

106,969

DESIGN FOR A PORTABLE POWER UNIT

John W. Fitz Gerald, Milwaukee, Wis., assignor
to Briggs & Stratton Corporation, Milwaukee,
Wis., a corporation of Delaware

Application April 5, 1937, Serial No. 68,558

Term of patent 14 years

To all whom it may concern:

Be it known, that I, John W. Fitz Gerald, a citizen of the United States, residing at Milwaukee, in the county of Milwaukee and State of Wisconsin, have invented a new, original, and ornamental Design for a Portable Power Unit, of which the following is a specification, reference being had to the accompanying drawing, forming part thereof.

Figure 1 is a perspective view of one side of a portable power unit showing my new design; and

I claim:

The ornamental design for a portable power unit, as shown.

JOHN W. FITZ GERALD.
